ATTORNEY

UNITED STATES PATENT OFFICE

138,592

DESIGN FOR AN ELECTRON SYMBOLS STENCIL

George T. Gillette, Garden City, N. Y.

Application May 29, 1944, Serial No. 113,803

Term of patent 7 years

(Cl. D52—1)

To all whom it may concern:

Be it known that I, George T. Gillette, a citizen of the United States, residing at Garden City, in the county of Nassau and State of New York, have invented a new, original, and ornamental Design for an Electron Symbols Stencil, of which the following is a specification, reference being had to the accompanying drawing, forming a part thereof.

Fig. 1 is a plan view of an electron symbols stencil, showing my new design; and

Fig. 2 is an edge view thereof.

I claim:

The ornamental design for an electron symbols stencil, as shown.

GEORGE T. GILLETTE.
